ATTORNEY

UNITED STATES PATENT OFFICE.

HENRY S. MICKS, OF CHICAGO, ILLINOIS.

CIRCUIT-CONTROLLING DEVICE.

Application filed February 16, 1927. Serial No. 188,857.

This invention relates to certain novel improvements in circuit controlling devices and has for its principal object the provision of an improved construction of this character which will be highly efficient in use and economical in manufacture.

The invention has for one of its salient objects the provision of an automatic controlling device which is incorporated in lighting circuits whereby electric lights remote from the controlling device will be automatically thrown into and from circuit with a source of electrical energy.

Other objects will appear hereinafter.

15 The invention consists in the novel combination and arrangement of parts to be hereinafter described and claimed.

The invention will be best understood by reference to the accompanying drawing, 20 showing the preferred form of construction, and in which:

Fig. 1 is a back view of an ordinary alarm clock showing the invention associated therewith,

25 Fig. 2 is a side elevational view of the same.

Fig. 3 is a side elevational view of an alarm clock showing a slightly modified form of construction associated therewith, and

30 Fig. 4 is a diagrammatical circuit arrangement embodied in the invention.

In the drawing, 10 indicates an alarm clock of the ordinary construction including the alarm hammer operating shaft. With this alarm clock I associate my controlling device. The controlling device includes a socket switch 11 of the pull chain type. This socket switch is connected to the back 11' of the alarm clock as at 12'. The exterior end portion of the alarm hammer shaft 12 has formed thereon a finger 13 provided with an open slot 14. The chain 15 of the socket switch is detachably connected to the finger 13 as at 16. Mounted in the socket 11 in one instance, is a fuse 17 of any approved construction. The socket switch is diagrammatically indicated in Fig. 4 and one side of the switch is connected to one side of a source of electrical energy 18 through the medium 45 of a conductor 19. The other side of the socket switch is connected in circuit with the

lighting elements 20 through the medium of conductors 12, said lighting elements being remotely disposed from the controlling device. The other side of the lighting elements 55 and the source of electrical energy is grounded as at 22.

In use, when it is desired to throw the lighting elements 20 in circuit with the source of electrical energy 18, the alarm of the clock 60 10 is set at the time when said circuit is to be completed through the medium of the alarm set button 23. When the mechanism of the clock, at the time set by the alarm button 23, is active the shaft 12 which rotates 65 the alarm hammer will rotate and this rotation will exert pull on the chain 15 whereby to operate the socket switch to close the circuit between the lighting elements 20 and source of electrical energy. To open the 70 circuit between the lighting elements 20 and source of electrical energy 18 the operation is substantially the same, it being pointed out that the time when the switch is to be operated is controlled by setting the alarm mechanism of the alarm clock at a particular time when it is desired to open or close the switch at a predetermined time.

In Fig. 3 the structure illustrated is substantially similar to the structure illustrated 80 in Fig. 2 with the exception that an indicating light 17' has been substituted for the fuse 17. Otherwise the operation is substantially the same.

By use of a controlling device as herein 85 described it will be apparent that lighting elements arranged in different buildings or lighting elements arranged in the same building remote from each other can be automatically thrown into and out of circuit with their 90 source of electrical energy.

I have not illustrated the specific structure of the socket switch because it is to be borne in mind that any approved type of socket switch may be used which includes a pull 95 chain.

While I have illustrated and described the preferred form of construction for carrying my invention into effect, this is capable of variation and modification without departing from the spirit of the invention. I, therefore, do not wish to be limited to the

precise details set forth but desire to avail myself of such variations and modifications as come within the scope of the appended claim.

5 The invention having been set forth, what I claim as new and desire to secure by Letters Patent is:

In a lighting circuit controlling device, the combination with the alarm hammer op-

erating shaft of an alarm clock, a socket 10 switch mounted on the back of the alarm clock and including a pull chain, and a finger formed on the shaft and having a notch 15 formed therein adapted to receive the outer end portion of the pull chain for operatively connecting the pull chain to the shaft.

In testimony whereof I affix my signature.

HENRY S. MICKS.
